UNITED STATES PATENT OFFICE.

RALPH L. LEE, OF DAYTON, OHIO, ASSIGNOR TO DELCO-LIGHT COMPANY, OF DAYTON, OHIO, A CORPORATION OF DELAWARE.

PUMPING APPARATUS.

Application filed November 26, 1923. Serial No. 677,171.

To all whom it may concern:

Be it known that I, RALPH L. LEE, a citizen of the United States of America, residing at Dayton, county of Montgomery, and 5 State of Ohio, have invented certain new and useful Improvements in Pumping Apparatus, of which the following is a full, clear, and exact description.

This invention relates to controlling devices for use in pumping systems, and more particularly to devices which are responsive to pressure in the system for automatically starting and stopping a power driven pump or pressure creating device.

10 It is among the objects of the invention to provide a controlling device which will be simple and reliable and tend toward a reduction in the number of parts.

In the disclosed form of the invention, a 20 motor driven pump is connected with a pressure storage tank, and a pressure responsive switch is connected with said tank. Increase of pressure in the system conditions the switch so that it can be operated by means 25 actuated by the pump driving mechanism in order to stop the pump automatically. Decrease of pressure causes a spring to be released to close the switch in order that the pump can be started automatically.

30 Further objects and advantages of the present invention will be apparent from the following description, reference being had to the accompanying drawings, wherein preferred embodiments of one form of the present invention are clearly shown.

In the drawings:

Fig. 1 is a diagrammatic view of a pumping system including the present invention.

Fig. 2 is a sectional view of the controlling device.

Fig. 3 is a sectional view taken on the line 3—3 of Fig. 2.

Referring to the drawings, and more particularly to Fig. 1, a pump 20 is provided 45 with an inlet pipe 21, and an outlet pipe 22 leading to a pressure storage tank 100. Tank 100 is connected with suitable supply pipes by outlet 101. A gear housing 30 supports an electric motor 40, having a motor shaft 41 journalled in a bearing 42 within said housing. A worm 43, carried by shaft 41, cooperates with a worm gear 44 within housing 30. Gear 44 carries an eccentric 45 provided with an eccentric strap 46 which 50 functions as a connecting rod between the

eccentric 45 and a cross head 46 which is adapted to be reciprocated in a cross head guide 47. A pump piston 23, which is adapted to be reciprocated in pump cylinder 24, is connected with cross head 46 by a 60 pump rod 25.

Housing 30 is provided with an opening 31 (see Figs. 2 and 3) in the top wall thereof. A plate 32 provides a cover for opening 31, and is provided with an opening 33 65 which is in alinement with opening 31. Plate 32 supports the controlling device represented as a whole by the numeral 50, a casting 51 therefor being secured to plate 32 by bolts 52.

70 The controlling device 50 includes a switch 54 and a pressure operated diaphragm 55 which is connected with tank 100 by pipe 102. A rotatable and longitudinally movable shaft 56 having a head 56^a is actuated 75 in one direction by diaphragm 55, against the action of a spring 55^a. Shaft 56 is provided with a reduced portion 57 which is 80 slideable through an aperture in an upwardly extending lug 58 carried by plate 32. 80

Switch 54 includes an upwardly extending supporting arm 59 of conducting material secured to plate 32 by bolt 60 but is insulated therefrom and arm 59 carries at its upper end a stationary contact 61 secured thereto 85 by screws 62. A conductor 110 connects the arm 59 and contact 61 with one terminal of motor 40. A conducting arm 65 is secured to shaft 56 by a pin 66 but is insulated therefrom, and carries at its upper end, as 90 viewed in Fig. 3, a resilient conducting strip 67, attached by screws 68. A contact 69, adapted for sliding engagement with contact 61, is secured adjacent the end of strip 67 by screws 70. Contact 69 is maintained 95 in engagement with contact 61, as shown in Fig. 3, by a coil spring 71, one end of which is attached to pin 72 carried by arm 65, the other end being connected with insulating pin 73 carried by arm 59. Conductor 111, 100 which is connected with arm 65 by a terminal clip 74 and screw 75, leads to a source of current such as a battery 112. Battery 112 is connected with the other terminal of motor 40 by wire 113.

105 The means actuated by the pump driving mechanism for operating the switch 54 comprises a cam 80 which is received by flattened portion 81 of shaft 41 and is held between the end of worm 43 and bearing 42 by a 110

spacing sleeve 82. The lower end of arm 65 extends through openings 33 and 31 into the gear housing 30, and carries an insulating pin 83 which is adapted to be moved into the path of cam 80, whereupon the arm 65 will be rotated in a counter-clockwise direction upon engagement of cam 80 therewith.

Means are provided for holding contact 69 out of engagement with contact 61. This means includes a supporting arm 90, carried by plate 32, which pivotally supports at 91 an arm 92 provided with a hooked end 93. A coil spring 94, having clips 95 secured to its opposite ends which engage pins 96 and 97 carried by arm 90 and arm 92 respectively, normally resiliently maintains arm 92 in engagement with stop pin 98 carried by arm 90. An insulating pin 99 is carried by arm 65 adjacent its upper end and is adapted to be moved into alignment with arm 92 and to be engaged by the hooked end 93 thereof when arm 65 is rotated by cam 80, thereby holding contact 69 out of engagement with contact 61.

25 Mode of operation.

Assume that the pressure in tank 100 has reached its predetermined low value. The parts of the controlling device will be in the position shown in the figures of the drawings, with the contacts 61 and 69 closed. The circuit will be as follows: from battery 112, through wire 113, motor 40, wire 110, arm 59, contact 61, contact 69, strip 67, arm 65 and conductor 111 back to the battery 112. The motor 40 operates worm 43 to drive worm gear 44, which through eccentric 45 and eccentric strap 46 causes cross head 46 to be reciprocated in cross head guide 47. This reciprocatory movement of cross head 46 is transmitted to pump piston 23 through pump rod 25, causing the pump 20 to take fluid in through pipe 21 and force the fluid into the tank 100 through outlet 22. As the tank 100 becomes filled with fluid and the air pressure therein increases to a predetermined high value, diaphragm 55 responds thereto and moves shaft 56 endwise to the right, as viewed in Fig. 2. As shaft 56 is moved in this direction, arm 65 is also moved along with it, moving pin 83 into the path of travel of cam 80 and the pin 99 into alignment with the hooked end of arm 92. Contact 69 slides along contact 61 and maintains the motor circuit. The switch is now conditioned by the diaphragm so as to be caused to open by means of the pump operating mechanism. When cam 80 strikes pin 83, the arm 65 will be rotated in a counterclockwise direction, separating contact 69 from contact 61, breaking the motor circuit and causing pin 99 to engage under the hook 93. Spring 94 will cause the hooked end 93 to hold arm 65 in such position that contacts 61 and 69 will

will be maintained in open position. As the pressure in tank 100 decreases, due to a demand on the system, the pressure on the diaphragm valve 55 will be relieved so that spring 55^a will move shaft 56 and arm 65 to the left, as viewed in Fig. 2; and when the predetermined low pressure is reached, pin 99 will have been moved out of alignment with the arm 92 and released from the hook end 93 thereof. Pin 83 is then out of alignment with cam 80. Spring 71 will then bring contact 69 into engagement with stationary contact 61 to complete the motor circuit, whereupon the motor will be started to cause the pump 20 to charge the tank 100 and restore pressure therein.

While the form of embodiment of the invention as herein disclosed, constitutes a preferred form, it is to be understood that other forms might be adopted, all coming within the scope of the claims which follow.

What is claimed is as follows:

1. A pumping system comprising, in combination, a storage tank, pressure means connected with said tank, a prime mover for said pressure means, driving mechanism between said prime mover and pressure means, a normally closed switch for controlling said prime mover, switch operating means actuated by the driving mechanism for operating said switch, but which means is normally disengaged from said switch so as not to operate the same, and means responsive to a rise in pressure in the system for conditioning said switch operating means so that the switch will be operated by the driving mechanism.

2. A pumping system comprising, in combination, a storage tank, a pump connected with said tank, an electric motor for driving said pump, driving mechanism between said motor and pump, a normally closed switch for controlling the motor, switch operating means actuated by the driving mechanism for operating said switch, but which means is normally disengaged from said switch so as not to operate the same, and means responsive to a rise in pressure in said storage tank for conditioning said switch operating means so that the switch will be operated by the driving mechanism.

3. A pumping system comprising, in combination, a storage tank, a pump connected with said tank, an electric motor for driving said pump, driving mechanism between said motor and pump, a switch including stationary and movable contacts normally in engagement with one another for controlling the motor, switch operating means actuated by the driving mechanism for moving the movable contact out of engagement with the stationary contact, means for holding the movable contact in disengaged position, and a pressure responsive device for conditioning said switch operat-

ing means so that the switch will be actuated by the driving mechanism, and for causing the movable contact to be released from said holding means.

- 5 4. A pumping system comprising, in combination, a pump adapted to supply water to said system to create pressure therein; an electric motor for operating said pump; a rotatable cam operated by said motor; an 10 oscillating and longitudinally movable shaft having an arm normally out of engagement with said cam, but which arm upon longitudinal movement of said shaft is brought into a position such that it will 15 be engaged by the cam aforesaid; a stationary contact member; a movable contact member carried by said arm; means for holding said contact members normally in engagement with one another; means oper- 20 able upon a rise of pressure in the system for imparting longitudinal movement to said shaft; and means for holding said movable contact out of engagement with said sta- 25 tionary contact after it has been moved away therefrom by said cam.

5. A pumping system comprising, in combination, a pump adapted to supply water to said system to create pressure therein; an electric motor for operating said pump; a rotatable cam operated by said motor; an 30 oscillating and longitudinally movable shaft; an arm carried by said shaft and partaking of the movements thereof; a stationary contact member; a movable contact member carried by said arm; means for 35 holding said movable contact member in engagement with said stationary contact member; means operable upon a rise of pressure in the system for imparting longitudinal movement to said shaft; a pivotally 40 supported holding member; and two pins carried by said arm and which pins are normally out of engagement with said cam and said holding member, but which pins are brought into positions to be engaged by said cam and holding member when said shaft is moved longitudinally as aforesaid.

In testimony whereof I hereto affix my signature.

RALPH L. LEE.
